DENTAL FLOSS DISPENSER

Irvin J. Gershen, Springfield, N.J., assignor to Johnson & Johnson, a corporation of New Jersey

Filed July 27, 1960, Ser. No. 61,538

Term of patent 14 years

(Cl. D24—1)

FIG. 1 is a perspective view of a dental floss dispenser showing my new design;

FIG. 2 is a plan view;

FIG. 3 is a front elevational view of FIG. 2;

FIG. 4 is a right side view of FIG. 3;

FIG. 5 is a rear view of FIG. 3;

FIG. 6 is a left side view of FIG. 3 and

FIG. 7 is a fragmentary cross-sectional view of FIG. 1, on an enlarged scale, taken along lines 7—7.

I claim:

The ornamental design for a dental floss dispenser, as shown.
